UNITED STATES PATENT OFFICE.

ADAM MORRIS, OF SUTERSVILLE, PENNSYLVANIA.

SAFETY-VALVE ATTACHMENT.

Application filed July 18, 1921. Serial No. 485,629.

To all whom it may concern:

Be it known that I, ADAM MORRIS, a citizen of the United States, residing at Sutersville, in the county of Westmoreland and

5 State of Pennsylvania, have invented new and useful Improvements in Safety-Valve Attachments, of which the following is a specification.

This invention comprehends the provision 10 of an automatic safety attachment for gas valves or the like, and by means of which the valve is automatically closed should the light be accidentally extinguished.

More specifically stated, the valve proper 15 is connected with yieldable means which is placed under tension when the valve is opened, electrically controlled means, embodying a thermostat being employed to hold the valve in its opened position against 20 the tension of the above mentioned yieldable means, and to release the valve automatically when the light is accidentally extinguished.

The nature and advantages of the invention will be better understood when the following detailed description is read in connection with the accompanying drawings, the invention residing in the construction, combination, and arrangement of parts as claimed.

30 In the drawings forming part of this application, like numerals of reference indicate similar parts in the several views and wherein:

Figure 1 is a side elevation of the invention.

Figure 2 is a front elevation.

Figure 3 is a top plan view.

Figure 4 is a diagrammatic view.

40 Figure 5 is a fragmentary view, showing the position of parts when the valve is opened.

Figure 6 is a rear elevation of certain elements of the invention.

Figure 7 is a vertical sectional view taken 45 on line 7—7 of Figure 2.

Figure 8 is a rear elevation of the element shown in Figure 7.

50 Figure 9 is a detail view of one part of the switch. Figure 10 is a diagrammatic view. Figure 11 is a detail view of the pivoted latch.

Referring to the drawings in detail, 10 indicates a feed pipe equipped with the usual rotary plug valve 11, the stem of which is indicated at 12. Associated with one end 55 of the pipe 10 is the curved extension or

elbow 13 of usual well known construction which has associated therewith the means for supporting the usual gas mantle 14 and the globe supporting member 15.

60 A two-part clamp 16 is secured to the stem 12 of the valve, and terminally connected with this clamp 16 is a coiled spring 17, the opposite end of which is secured to a fixed bracket 18. The spring 17 is employed 65 to automatically move the valve from its opened to its closed position in a manner to be hereinafter more fully described.

Supported by one end of the valve is a base plate 20 which has secured thereto a 70 plurality of binding posts 21 with which the terminals of various wires are connected, these wires being indicated at 23 and 24 respectively. Also supported by the said valve is a bracket 24' which has mounted 75 thereon a magnet 25 associated with the valve in a manner to turn with the latter, and in order to retain the valve in opened position against the tension of the spring 17, the bracket 24' which supports the magnet 80 85 also supports a pivoted locking element 26 which is designed to engage the teeth 27 of a rack bar 28 which is mounted upon the pipe 10 adjacent the valve 11. The locking element 26 terminates to provide a singly engaged portion 29 whereby the locking element may be released from the rack bar manually when desired, although the locking element is arranged to be controlled by the magnet 25 in a manner to be hereinafter 90 95 described.

A switch including a fixed contact 31, and a movable contact 32 is connected in circuit with the magnet 25, and when this switch is closed, the said magnet 25 is energized. 95 The movable contact 32 is carried by the valve for rotation therewith, and when the valve is opened, the movable contact 32 is brought into engagement with the fixed contact 31. In other words, the switch just described is closed when the valve 11 is opened, but the magnet 25 does not become energized until the circuit is closed, through the switch, this circuit including a thermostat indicated generally at A and which is connected in circuit with the switch referred to.

100 The thermostat A may be of any suitable construction, and is supported by a bracket 33 upon the curved extension 13 of the pipe 110 10 and the globe supporting member 15. The thermostat includes a fixed contact 35

which is normally engaged by the movable indicator 36, whereby the thermostat is included in the circuit. The operation of the invention is as follows:

5 When the valve 11 is opened, the spring 17 is tensioned, and the locking element 26 gravitates into operative association with the rack bar to hold this valve open against the tension of said spring. When the 10 burner is lighted, the thermostat is put into operation, whereupon the indicator moves across the face of the thermostat and away from the fixed contact 35, thus opening the circuit. When the valve 11 is opened, the 15 switch including the fixed and movable contact 31 and 32 respectively, is closed, but the magnet 25 is not energized because the circuit including the thermostat A is open. Now, should the burner for any reason become accidentally extinguished, the thermostat A is affected in a manner which allows the indicator to return to normal position into engagement with the fixed contact 35, thereby closing the circuit through the switch 20 above referred to, energizing the magnet 25. When the magnet is energized, it attracts and moves the locking element 26 away from the rackbar 28, thereby releasing the valve so that the latter is automatically returned to its closed position under the 25 influence of the spring 17. When the valve is thus moved to its closed position, the movable contact 32 of the switch is separated from the fixed contact 31, thus again opening the circuit. The source of energy for 30 said circuit is indicated at 37. The safety attachment is both simple in construction

and efficient in operation for the purpose intended.

While it is believed that from the foregoing description the nature and advantages of the invention will be readily apparent, I desire to have it understood that I do not limit myself to what is herein shown and described, and that such changes may be resorted to when desired as fall within the scope of what is claimed.

What I claim is:

A device of the character described, a gas conducting pipe provided with a rotary valve, resilient means for normally holding the valve in closed position, a rack bar supported at one side of the valve, an electro-magnet fixed to rotate with the valve, a latch element carried by the armature of the electro-magnet and adapted to normally engage the rack bar whereby to hold the valve in open position against the action of the spring, and an electric circuit, an electric device for the circuit including fixed and movable contacts and electrically connected with the electro-magnet, said electric device normally rendering the electro-magnet inoperative and operating to energize the magnet when under abnormal conditions the movable contact engaging the fixed contact of the electric device to complete the circuit through the magnet whereby to disengage the latch element from the rack bar to permit the valve to close, and means operated upon the manual rotation of the valve to make and break the electric circuit.

In testimony whereof I affix my signature.

ADAM MORRIS.
